AIRCRAFT FLOAT LIGHT

Max J. Eichschmidt, Elkton, Md.

Application October 19, 1936, Serial No. 106,471

2 Claims. (Cl. 102—24)

This invention relates to lighting devices of the signal type, and more particularly to a light which is operated by impact.

An object of this invention is to provide an improved lighting means for use with aircraft which is so constructed that it will readily ignite by falling into water, the device being sufficiently buoyant to prevent the water from putting the light out.

Another object of this invention is to provide an aircraft float light having a firing pin so mounted that moisture cannot interfere with the operation thereof, so that when the nose carrying the firing pin strikes water the firing pin will perform its necessary operation in setting off the light.

A further object of this invention is to provide a float light of this character which is so constructed that the same degree or period of light can be obtained from a device which is appreciably smaller in size and weight, so that a considerable number of the lighting devices may be carried in an airplane without unduly affecting the carrying capacity of the airplane.

A still further object of this invention is to provide a signal device which is so constructed that it will not ignite in the event the wrong end strikes first, and will not ignite in the event either end thereof strikes a hard surface, so that the device is thereby rendered safe for use by airplanes in that no signal light will be operated if the flare is dropped and strikes buildings, land, or any hard object or surface other than water or mud.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a longitudinal section taken through substantially the center of a device constructed according to an embodiment of this invention.

Figure 2 is a fragmentary detail side elevation partly broken away and in section.

Figure 3 is an end elevation of the upper end of the device.

Figure 4 is an end elevation of the lower end of the device.

Figure 5 is a sectional view taken on the line 5—5 of Fig. 1.

Referring to the drawing, the numeral 10 designates generally a tubular member comprising the outer shell of a lighting device constructed

according to an embodiment of this invention. Preferably this shell 10 is constructed of relatively light weight material, such as paper or like fibrous material, which will not readily burst under the initial expansion of gases therein.

The front or lower end of the shell 10 engages the reduced inner end portion 11 of a head 12, and preferably the reduced portion 11 of the head 12 is provided with annular ribs 13. A compression or clamping ring 15 engages about the forward end of the shell 10 and holds this shell 10 tightly on the ribs 13 and against the shoulder 14 formed by reducing the upper end of the head 12.

A pyrotechnic casing 16 is disposed within the shell 10 adjacent the lower end thereof, and is constructed in the form of a metal cylinder 17 having a pellet 18 on the inside thereof through which a fuse 19 extends. The upper or inner end of the cylinder 17 is constructed in the form of a cone, as at 20, and preferably this cone is frangible and contains a pellet igniting charge 21.

The inner end of the pyrotechnic casing 16 is seated in a recess 22 provided in a plug 23. The plug 23 has a bore 24 relatively smaller in diameter than the diameter of the pyrotechnic casing 16, and this plug 23 is secured to the shell 10 by means of nails 25 or other suitable fastening devices. A cylindrical member 26 is disposed within the shell upwardly of the plug 23, the cylindrical member 26 being constructed of substantially the same material as the shell 10. This member 26 is firmly held against the upper end of the plug 23 by means of nails 27 or the like.

The casing 17 is held concentrically within the shell 10 by means of a plurality of circumferentially spaced apart longitudinally extending sticks or bars 28 which are held in proper position by means of a wire 29 extending through suitable holes 30 provided in the bars 28. These bars or sticks 28 not only serve the purpose of holding the casing 17 concentrically within the shell 10, but also operate to reinforce the casing 17.

A priming cap holder and casing closure 36 is held in the lower end of the metal cylinder 17 by crimping, and a reduced axial portion 37 thereof is threaded into the head 12. This reduced portion 37 is provided with an axial bore 31 in which the forward end of the fuse 19 engages for a portion of the length thereof. A cylindrical extension 38 of the holder 36 extends through an enlarged bore or chamber 39 pro-

vided in the head 12, and this extension 38 is provided with a relatively small bore 40 intersecting near its inner end with a transversely extending passage 41 which is disposed near the lower or outer end of the bore 31. A priming cap 42 is held by crimping as at 43 onto the outer or lower end of the extension 38 and closes the outer end of the opening 40.

The closed inner end of the casing 17 has a container or cup 32 mounted therein provided with a cylindrical flange 33, and a combustible disk 34 is interposed between the flange 33 and the inner end of the pellet 18. The fuse 19 extends into the container 32 which holds the starting mixture 21, and a quick starting igniter 35 is disposed within the container 32 in a position for ignition by the fuse 19.

The head 12 is provided at its outer or lower end with a truncated or flaring recess 44, and a relatively flexible disk or diaphragm 45 extends across this recess 44. A nose 46 engages against the outer side of the diaphragm 45, being held thereagainst by crimping the outer or lower end of the body 12, as at 47. The nose 46 is preferably constructed of metal so as to provide a sufficient weight at the lower end of the shell 10 to cause this end thereof to assume the lead when the device is falling. The nose 46 has an axial passage 48 therethrough, which at its outer or lower end is flared as at 49, this passage 48 comprising a compression chamber by means of which the diaphragm 45 is flexed inwardly.

The diaphragm 45 is provided with a firing pin 50 which confronts the primer 42, this firing pin 50 being relatively short so that the flexing of the diaphragm 45 inwardly will effect contact of the firing pin 50 with the primer 42, as shown in Fig. 2.

The upper or rear end of the shell 10 is provided with direction fins 51 which are constructed from a sheet of material which is bent upon itself to provide the desired number of radial fins 51 and then bent in cylindrical form to closely engage about the periphery of the shell 10. A plug 52 is disposed within the upper or rear end of the shell 10, being provided with a bore 53 which is closed by means of a dished plate or closure 54 which engages in an enlarged recess 55 at the upper end of the plug 52. The plate 54 is provided with a plurality of vent openings 56 by means of which the gases in the combustion chamber 57 may be initially released. The plug 52 is preferably flanged at its outer end as at 58, this annular flange 58 engaging against the upper end of the shell 10. The plug 52 and the fins or blades 51 are securely held in position by means of nails 59 or like fastening devices which pass through the cylindrical body portion 60, through the shell 10 and into the plug 52, the plug 52 being preferably constructed of wood or fibrous material.

In the use of this aircraft float light, the device may be dropped from an airplane from a suitable height, and the weight of the lower end thereof will cause the nose 46 to take the lead, with the fins 51 holding the shell 10 in a relatively straight line to prevent tumbling thereof. Assuming that this light is dropped into water from a suitable height, when the nose 46 strikes the water, a jet of water will enter the chamber 48 and will flex the diaphragm 45 inwardly and cause the firing pin 50 to contact with the priming cap 42. The charge of the priming cap 42 will pass inwardly through the passage 40 and

the bore 31, thereby igniting the delay or starting fuse 19.

It will, of course, be understood that when the device is dropped into the water it will be submerged for a period of time until the buoyancy thereof will bring the device to the surface of the water. During the time that the device is submerged, the fuse 19 is slowly burning, the time of burning of this fuse 19 being about ten seconds; although of course the time of burning of the fuse 19 may be varied by different combinations of fuse material.

When the fire from the fuse 19 reaches the starter mixture container 32, the igniter 35 will be ignited and this will in turn ignite the starter mixture 21 which will then burn the combustible disk or wall 34. At the same time that the upper end of the pellet 18 is ignited through the burning of the combustible disk or wall 34, the cap 20 will be fractured. The expansion of gases caused by ignition of the powder 21 in the container 32 will blow out the plate or closure 54, so that by the time that the pellet 18 is ignited the flame therefrom can readily project through the bore of the plug 52.

The diaphragm 45 is preferably constructed of metal so that moisture will not affect the condition thereof, and so that the force of the device striking the water will not fracture the diaphragm and permit water to enter the lower end of the head 12 and thus prevent proper lighting of the lighting charge 18.

This light by reason of its compactness can be made considerably smaller than lights which do not embody an impact lighting means of this character, and in addition the construction cost of the light is thereby reduced to an appreciable extent.

It is obvious that various changes and modifications may be made in the details of construction and design of the above specifically described embodiment of this invention without departing from the spirit thereof, such changes and modifications being restricted only by the scope of the following claims.

What is claimed is:

1. A device as described comprising a head having a through opening in a central portion and a substantially frusto conical recess in its lower end portion with the wider end of the recess presented downwardly and reaching out to a diameter just short of the external diameter of the head, a resilient diaphragm of a diameter approaching that of the head seated at its marginal edge upon the enlarged base portion of the frusto conical recess, a perforated nose fitted below and in contact with the normal sprung condition of the resilient diaphragm and having a marginal flange, a downwardly projecting rim on said head extending in common about the margins of said diaphragm and nose flange and being crimped inwardly upon the nose to form a tight fastening for the marginal edge portion only of the diaphragm, firing means carried by an intermediate portion of the diaphragm, a pyrotechnic unit having its forward end supported by said head having a forward projection extending through the opening in said head, a primer carried by said projection in the upper narrower part of said recess opposite said firing means, a shell having its forward end affixed to said head and surrounding said pyrotechnic unit, and means in said shell for supporting the rear portion of said pyrotechnic unit.

2. A device as described comprising a head

having a through opening in a central portion and a substantially frusto conical recess in its lower end portion with the wider end of the recess presented downwardly and reaching out to a diameter just short of the external diameter of the head, a resilient diaphragm of a diameter approaching that of the head seated at its marginal edge upon the enlarged base portion of the frusto conical recess, a perforated nose fitted below and in contact with the normal sprung condition of the resilient diaphragm and having a marginal flange, a downwardly projecting rim on said head extending in common about the margins of said diaphragm and nose flange and being crimped inwardly upon the nose to form a tight fastening for the marginal edge portion

only of the diaphragm, firing means carried by an intermediate portion of the diaphragm, a pyrotechnic unit having its forward end supported by said head having a forward projection extending through the opening in said head, a primer carried by said projection in the upper narrower part of said recess opposite said firing means, a paper shell having its lower end overlapping with a part of said head, means for binding the overlapped part of said paper shell upon said head, a perforated ring fixed in an intermediate portion of said paper shell having means to receive and support the upper end of the pyrotechnic unit.
